CLAIM

The ornamental design for an accessory connector for a portable communications device, as shown and described.

DESCRIPTION

FIG. 1 is a front isometric view showing a contact area of our new design;

FIG. 2 is rear isometric view showing the housing contour thereof;

FIG. 3 is a left side view thereof;

FIG. 4 is a right side view thereof;

FIG. 5 is a top plan view thereof;

FIG. 6 is a bottom plan view thereof;

FIG. 7 is front elevational view; and,

FIG. 8 is a rear elevational view.

The broken lines shown in FIGS. 1-2, 5, and 7 are included for the purpose of illustrating environmental elements only and form no part of the claimed design.
